UNITED STATES PATENT OFFICE.

EDWARD SOKAL, OF NEW YORK, N. Y., ASSIGNOR TO AMERICAN KATALITE CORPORATION.

INTERNAL-COMBUSTION ENGINE.

Application filed October 13, 1920. Serial No. 416,736.

To all whom it may concern:

Be it known that I, EDWARD SOKAL, a citizen of the United States, residing at New York, in the county of New York and State of New York, have invented certain new and useful Improvements in Internal-Combustion Engines, of which the following is a full, clear, and exact description, such as will enable others skilled in the art to 10 which it appertains to make and use the same.

This invention relates to internal combustion engines.

It is an object of the invention to provide 15 simple and efficient means for improving the combustion of fuel mixtures in engines of the character mentioned.

It is a further object to provide improved means capable of wide application and 20 wherewith notable and manifold advantages in the operation of internal combustion engines may be secured.

Broadly speaking, internal combustion engines are of the constant volume and constant 25 pressure types. In the former it is usual to operate on a cycle wherein a combustible mixture of air and gas, or volatilized fuel, is compressed to a definite volume and ignited to increase sharply the pressure utilized 30 on the succeeding expansion or power stroke. Engines of this character are, for example, standard practice in the automotive industry, and the operation thereof and certain of the more general objections thereto are 35 popularly known. For example, difficulties increasingly burdensome are encountered by reason of the deteriorating quality and increasing cost of the gasoline used for carburetting to the combustible mixture. At- 40 tendant objections, such as incomplete combustion with carbon deposition, and its resultant ills, are familiar and have heretofore received widely diversified and special attention.

Engines of the constant pressure type, for 45 example, the well known Diesel engine, operate on a cycle wherein, generally speaking, a non-combustible gas is more highly compressed and reaches a definite temperature 50 at which, on the injection of an oil fuel, the mixture ignites and a relatively constant increased pressure is rendered available on the succeeding power stroke. Engines of this character commonly employ 55 the lower grade fuels and a matter of con-

siderable economy is thus effected as well as increased thermal efficiencies by reason of the higher compressions thus permitted. The accompanying disadvantages, however, (increased weight required in the engine 60 structure, difficulty in starting, and limited flexibility, among others) have heretofore restricted the field of useful application of these engines.

The present invention, generically considered, is capable of embodiment in both types of engines above mentioned as well as in others, and is designed to contribute common advantages thereto as well as to tend to overcome the disadvantages peculiar 65 to each form.

For a more complete understanding of the nature and advantages of this invention reference should be had to the following detailed description, which describes the best 75 illustrative embodiments of this invention at present known to me, taken in connection with the accompanying drawing in which:

Figure 1 is a side elevation of an internal combustion engine, part being broken away 80 which is constructed to embody this invention; and

Figure 2 is a fragmentary sectional view of a cylinder of an internal combustion engine showing a modified embodiment of 85 this invention.

Referring now to the drawing, and particularly to Fig. 1, 10 denotes a two cylinder internal combustion engine, having a combustion chamber as shown at 11. In 90 the chamber 11 there reciprocates a piston 12, ignition being effected in the combustion chamber in the usual manner by a spark from the spark plug shown at 13.

In carrying the present invention into 95 effect, there is disposed in the combustion chamber of an internal combustion engine an agent which provides a permanently exposed surface functioning to facilitate and improve but not to institute the combustion 100 of the carburetted air or other fuel mixture within the combustion chamber. This agent by its presence appears to act as an effective accelerant for accelerating combustion although not producing it, and may be regarded as a species of catalyst.

The theory of catalysis is somewhat controversial. In some books it is stated that catalysis is a phenomenon in which a substance alters the velocity of a chemical re- 110

- action without undergoing itself any permanent change. This would be analogous in a way, to the fact for instance, that a good electrical conductor can hasten the flow 5 of electricity from one point to another without undergoing itself any permanent change. The above is the most generally accepted definition and usually it refers, as it does in our case, to a substance which accelerates 10 the speed of the chemical reaction while it might also apply to a substance which would retard the speed of the chemical reaction, which substances are then called negative catalyst.
- 15 By another definition, which is less frequent and authoritative, catalysis is a phenomenon by which a substance may not only influence but actually start a chemical reaction which would otherwise not take place,
- 20 and in which the catalyst may be deemed to undergo some change, since it does not act merely by being present.

Theoretically the difference between these definitions is quite important, but in the present state of the science sufficient data is not at hand definitely to decide the question. This is partly due to the difficulty in observing exceedingly small quantities of the catalyst which may enter into the 25 reaction. In the technical application of the definitions however, distinctions between starting a reaction and accelerating a reaction resolves itself into a consideration of practical accomplishments, and from this 30 standpoint may not only justify but require specific names for separate effects.

In order, therefore, to distinguish the agent here employed as a catalyst from those which by their mere presence are 40 designed to produce chemical action, the catalyst of this invention is styled a "catalyzer" which is effectively accelerant", which term is intended to signify only such material or compound as advantageously affects the 45 combustion of the fuel mixture when ignition is accomplished by an independent means, and does not itself undergo any permanent change.

In Fig. 1 the presence of the catalyzing agent is shown by the heavy line at 14, which indicates a coating or exposed surface of the agent on the upper wall of the combustion chamber 11.

The disposition of the catalyzer in the combustion chamber is susceptible of being accomplished in a variety of ways. Its relative location within the chamber may also be chosen as desired. For example 55 the catalyzer may be applied either directly to the cylinder wall as shown at 14 in Fig. 1, or to the surface of a support as shown at 60 15 in Fig. 2. The support may be secured to the cylinder wall, or to the cylinder head in proximity to the ordinary igniting device, 65 or spark plug, such as is shown at 13' in

Fig. 2. In certain instances its operative exposure to the fuel mixture may be governed when desired. In research and test with respect to my invention, I have up to the present time found it preferable to 70 employ a metallic oxide which is refractory and substantially infusible at the temperatures of combustion as the catalyzing agent and it is desirable to utilize for the purpose a metallic oxide which, by reason of its 75 manufacturing economy, its refractory character and its resistance to so-called poisoning, best fulfills the requirements of cheapness, reliability and permanence. One material which I have found to combine 80 efficiently the qualities referred to, among others, is aluminum oxide (Al_2O_3), and the manner of carrying out the invention with this material will now be described:

Aluminum sulphate $Al_2(SO_4)_3$ or aluminum nitrate $Al(NO_3)_3$ may be combined with a base as powdered clay shale, in proportions varying within limits on either side from 50% of each, and the whole rendered plastic with water to 85 form a paste. This material may then be spread on a screen or other holding element or binder and subjected to heat, as by gradual baking to 900 degrees centigrade, for 90 reducing the aluminum to the oxide (Al_2O_3) which is the active agent and for consolidating the mass and rendering it cohesive. After baking, the catalyst secured in the combustion chamber may be scraped to 95 present a clean surface.

Cerium oxide (CeO_2) is in certain respects an equivalent catalyzing agent. The present cost of this material is considerably higher than the aluminum oxide, but on the other hand it is perhaps chemically more 100 resistant to deterioration or poisoning under the influence of the high temperatures and pressures of the combustible and burned gases encountered in gas engine operation. With this material also the production may 105 be as above set forth, starting from the cerium sulphate or cerium nitrate and mixing with a refractory and inert base with final reduction to the cerium oxide (CeO_2).

The oxides above described, whether used 110 separately or in mixtures yield catalytic agents which are effectively accelerant in accordance with this invention and substantially do not enter into the combustion reaction. Such an agent is well adapted to be 115 permanently exposed within the combustion chamber, as it is solid, refractory and has a relatively high coefficient of radiation.

In operation the catalyzer, by reason of 120 an action not yet thoroughly understood or uniformly explained, influences the combustion of the fuel mixture when ignited. It is to be noted that the common electrical, 125 or other, ignition of the charge is retained and that the catalyzer consequently exerts 130

its effect to facilitate and to improve the combustion of the charge after the ignition is otherwise effected.

In practice it is found that with engines embodying my invention as described, increased useful power may be secured per unit of fuel consumed. The advantages of the invention furthermore may be considered in additional aspects. That is to say, for example, in comparison with standard engines, my improved engines will deliver equal power with less fuel consumption; in other words, leaner mixtures may be employed with increased net efficiency. I have found, for example, that it is possible to employ a mixture so lean in the fuel content as to be otherwise incapable of efficient combustion. A further refinement of internal combustion engines is therefore rendered possible, wherein the compression ratio may be increased and higher thermal efficiencies thereby secured.

Not only is the combustion of the ignited charge facilitated but the time of combustion, that is the interval between the ignition and maximum pressure, is decreased very materially, and furthermore, the completeness of the combustion is enhanced to a degree where, in practice, I have found a complete elimination of free carbon from the burned gases so that after a prolonged interval of operation an examination of the combustion chamber has shown no trace of carbon deposition.

A further advantage resulting from the use of a coating of catalyzer, disposed in accordance with this invention, is the cooling effect which follows. This catalyzer operates to prevent the walls of the combustion chamber from absorbing as much heat as when not used, engines embodying this invention having operated noticeably longer in a cooler condition than formerly. As a consequence the consumption of lubricating oil by engines embodying this invention is also very much less than would have been the case if the invention had not been employed.

Among the more readily understood advantages of the invention may be mentioned the attainment of easier starting, quicker acceleration, fuel economy, the use of less volatile fuels, greater flexibility of the engine in operation, the elimination of carbon deposit, the prevention of pre-ignition and knocking, and increased thermal efficiency, the tendency to prevent knocking in such cases results from the improved completion of combustion.

It will be understood also that the embodiment of the invention in engines of the constant pressure type permits the employment of lower compression ratios and consequently lessened engine weights, starting is rendered easier, and the range of flexi-

bility increased; the use of engines of the Diesel or semi-Diesel type consequently becomes permissible in an increasing field of application and in smaller horsepower units.

From the foregoing description of the invention and the reference (not intended to be complete) to certain of the objections encountered with present day internal combustion motors, and certain of the advantages and capabilities for improvement in the design and operation thereof gained or rendered possible by the present invention, the far reaching scope of the present invention will become apparent. It is, therefore, to be understood that the appended claims are intended to be generic as well as specific and that the invention is capable of application and efficient utilization through a wide range of embodiments without sacrifice of the major advantages.

Having described by invention, what I claim as new and desire to secure by Letters Patent, is as follows:

1. In an internal combustion engine, in combination, a combustion chamber for the fuel charge including means to ignite the charge, and an accelerating catalyzer functionally independent of said igniting means fixedly disposed in said combustion chamber to promote the combustion of the otherwise ignited charge.

2. In an internal combustion engine, in combination, a combustion chamber for a compressed fuel charge, means to ignite the mixture locally at an instant predetermined but variable with respect to the degree of compression of the charge, and a solid effectively accelerant catalyzer located within said combustion chamber to promote the combustion of the otherwise ignited charge.

3. In an internal combustion engine, in combination, a chamber for a compressed fuel charge, timed sparking means to ignite the charge, and a catalyzing agent permanently disposed in the combustion chamber and of a character to accelerate and promote the combustion of the charge but incapable of effecting ignition thereof during normal designed operation of the engine.

4. In an internal combustion engine, in combination, a combustion cylinder having intake and exhaust valves, electrical ignition means to locally fire the fuel charge, and a substance secured within said cylinder and exposed to the charge and of a character to accelerate the combustion thereof without undergoing permanent substantial change itself.

5. In an internal combustion engine, the combination with a combustion chamber for the fuel charge having means to abruptly effect ignition of the charge, of an effectively accelerant catalyzing agent fixedly disposed interiorly of said chamber and com-

prising a refractory metal oxide permanently exposed to the charge.

6. A method of effecting and improving combustion in internal combustion engines which comprises permanently exposing within the combustion chamber an agent which is effectively accelerant in its action during combustion but is incapable of initiating combustion, and independently initiating combustion at the desired instant.

7. The step in the method of effecting

combustion in an internal combustion engine which comprises accelerating and rendering more complete the combustive reaction after ignition has been initiated by functionally independent means, said acceleration being accomplished by permanently exposing to the fuel mixture in the combustion chamber a solid, refractory, accelerant catalyzer having a high coefficient of radiation.

In testimony whereof I affix my signature.

EDWARD SOKAL.
